UNITED STATES PATENT OFFICE.

CHARLES A. FRAYER, OF TOLEDO, OHIO, ASSIGNEE, BY MESNE ASSIGNMENTS, TO THE BUCYRUS COMPANY, OF SOUTH MILWAUKEE, WISCONSIN, A CORPORATION OF WISCONSIN.

BUCKET MECHANISM.

1,032,358.

Specification of Letters Patent.

Patented July 9, 1912.

Application filed January 20, 1910. Serial No. 539,049.

To all whom it may concern:

Be it known that I, CHARLES A. FRAYER, a citizen of the United States, residing at Toledo, Lucas county, Ohio, have invented 5 new and useful Bucket Mechanism, of which the following is a specification.

This invention relates to devices for moving material or excavating.

This invention has utility when embodied 10 in excavator buckets of the drag line type.

Referring to the drawings: Figure 1 is a side elevation, with parts broken away, showing an embodiment of the invention as adapted for use in connection with a swing- 15 ing boom crane; Fig. 2 is a longitudinal medial section, on an enlarged scale showing the devices of the invention as adapted to the drag line bucket operation; and Fig. 3 is a plan view of the bucket, with parts 20 broken away.

The rotatable platform 1 has mounted thereon the prime mover 2 and the boom 3. The angle of the boom 3 may be adjusted by the line 4, while the hoisting or suspension 25 line 5 and the drag or haul line 6 extend to the bucket 7. The hoisting line 5 engages the suspension arm 8 pivotally mounted on the bucket 7 within the width of the bucket. The suspension arm 8 has mounted therein 30 roller carrying pin 9 movable into the notch 10 of the pivoted holding device 11. This trip or holding device 11 has pivot pin 12 mounting it on the bucket. To keep this device from swinging too close to the bucket 35 7, it has pin 13 riding upon the walls of the channel bucket top. This pin 13 rides in slot 14 of the reciprocable tripping element or trigger 15 of the holding device. This element 15 is guided by the sleeve 16 40 in its reciprocations to force the pin 9 out of the notch 10, and may not move to a vertical position owing to pin 12 over which it rides and as to which it is held by sleeve 16. The sleeve 16 is pivotally mounted by the 45 pin 13 in the forks of the holding device or hook 11 carried by the pin 12.

Pivottally connected to the forward end of the bucket 7 is the draw member 17 having the way 18 in which is reciprocable the block 19, about which block 19 the drag line 6 extends before being connected to the draw member 17. Connected to the block 19 is the pair of flexible connections 20 extending through guides 21 on the bucket 7 to the eyes 22 on the arm sections 8, to limit 50 the oscillation of the bucket. To limit the

oscillation of the draw member 17 as well as to permit element 15 to get in position to allow resetting of the holding device, connections are provided from bracket 23, by 60 means of line 24 to the eyes 25 on the suspension arm sections 8. This line 24 also limits the swing of the bucket relatively to the draw member and suspending arm. The bucket 7 is shown in this instance as provided with a pivoted back, to aid in the dumping operation. To supplement the freeing of material tending to adhere to the bucket back, the showing embodies the back frame 26 having an openwork back therein 65 comprising chain links 27, which in the handling of the bucket will vibrate and thus shake material free therefrom. As an extension from this screen back, is shown the hinged member 28, which has a scooping 70 action in the dumping operation. The pivoted back is shown as directly connected to the suspension arms 8 to be movable therewith. The bucket bottom is provided with longitudinally extending guiding and scoring 75 vanes 29, effective not only to keep the bucket lined up for proper travel in the digging operations, but also serving to loosen up the material, thereby aiding subsequent filling of the bucket. To permit 80 adjustment of the forward limit of travel of the block 19, openings 30 are provided in the member 17, in which openings pin 31 may be inserted.

In operation, the platform 1 is swung so 85 that the boom 3 hangs over or toward the material to be moved, and the hoist line 5 is so paid out that the bucket 7 may properly land in position thereon as guided by the drag line 6. The scoring vanes 29 engaging 90 in the loose material, tend to keep the bucket 7 from working out of line of the haul cable 6 during the filling of the bucket. With tension upon the haul line 6, block 19 is drawn to its forward limit of travel along 95 the way 18, which causes the drag member 17 to be inclined downwardly due to the connections 20. This deflection of the member 17 is adjustable by the pin 31 varying 100 the forward limit of travel of the block 19. By this adjustment the angle of travel of the bucket into the material may be regulated, the draw member having a sort of plow beam action. In this travel the back of the bucket is closed and pin 9 of the suspension 105 arm 8 is engaged by the holding device 11, as shown in full lines in Fig. 1 or in dotted

lines in Fig. 2. When the bucket 7 is filled, it is lifted by the hoisting line 5, draw line 6 being paid out sufficiently to control the position of the bucket, while the platform 1 is 5 swung to bring the boom 3 into position over the dumping place for the material. With the bucket 7 thus suspended for dumping, the draw line 6 is slackened, which permits the heavy outer end of the draw member 17 to 10 swing downward, as shown in dotted lines in Fig. 2, which travel of this member 17 in the path of element 15 brings about a contact by member 17 with the lower end of this element 15, which concussion pushes 15 element 15 from the full line position to the dotted line position shown in Fig. 2, thus effecting movement of this element 15 into the notch 10 to force pin 9 out of this notch, thereby tripping the bucket 7, permitting 20 the released forward end of the bucket to swing downward as shown in full lines in Fig. 2. In this swinging operation, the line 24 pulls the draw member up so that it may not interfere with the free fall of material 25 being discharged from the bucket. The slackening of line 6 permits the block 19 to travel toward the inner end of the way 18 as guide 21 pulls the connections 20 to the limit of the bucket oscillation. Simultane- 30 usly with this inclining of the bucket, the back 26, due to its connection with arm 8, swings forward relatively to the bucket, with its extension 28 scooping the material out of the bucket 7. The more or less vio- 35 lence attending this dumping operation shakes the chain links 27 to free any material tending to stick thereto. Tendency to clog the bucket is therefore avoided, while the advantages of draining are assured. As 40 member 17 was swung upward in the dumping operation, the element 15 moved back to leave the notch 10 clear. After dumping, the slack in line 6 is taken up, drawing block 19 forward, causing line 20 to lift the 45 forward end of the bucket, with line 24 drawing the arm 8 so that pin 9 will ride against the pivoted holding device 11 to engage the notch 10, when the refilling of the bucket for continued operation may 50 occur. This resetting of the releasable trip may be had as the bucket is being returned for load. The device is accordingly sus- 55 ceptible of rapid operation from the regular drag and hoist lines without the introduction of any complications to hamper simple and efficient handling. The drag and hoist lines may even be manipulated for swinging the bucket beyond the boom end for landing or dumping.

60 What is claimed and it is desired to secure by Letters Patent is:

1. A bucket, a trip connected to the bucket, a hoisting member for the bucket and detachably connected to the trip to hold 65 the bucket in material retaining position, a

drag line, a connecting beam between the drag line and the bucket, and connecting means to the trip engaging the beam between the bucket and drag line and effective by slackening of the drag line to detach the trip from holding the bucket in material retaining position. 70

2. A bucket, a suspending arm therefor, a return line for the bucket connected to the suspending arm, a trip mounted on the 75 bucket and having a trigger, said trip detachably connected to the arm to hold the arm from movement relatively to the bucket, and in addition to the suspending arm a drag line to the bucket and provided with 80 means movable upon slackening of the drag line to move the trigger to disconnect the arm from the trip to permit free swinging of the return line held arm as to the bucket at different positions of the bucket. 85

3. A bucket, a disconnecting trip for the bucket, a hoisting member engaged by the trip, a draw member mounted on the bucket and movable relatively to the bucket to actuate the trip, and a drag line connected to the 90 member and effective by slackening to cause the draw member to actuate the trip to disconnect the hoisting member for free swinging relatively to the bucket. 95

4. A bucket, a drag line for the bucket to 100 actuate the bucket in one direction, a return line for the bucket to actuate the bucket in the reverse direction, in addition to said lines a suspending arm pivoted to the bucket and coacting with one of the lines, and a 105 trip carried by the bucket and provided with a trigger to hold the arm, said drag line provided with means movable upon slackening of the drag line to reciprocate said trigger to release the trip from the arm to thereby free the arm.

5. A bucket, a draw member and a suspending arm each pivotally and separately connected to the bucket, and a trigger trip connected to hold the bucket as to the suspending arm, said trigger disconnected by 110 rocking of the draw member as to the bucket to free the arm and thus permit swinging of the bucket relatively to the arm. 115

6. A bucket, a draw member and a suspending arm each pivotally and separately connected to the bucket, a holding device for the arm embodying a draw member actuated element, and a drag line to the member operable on slackening to permit falling of 120 the draw member as to the bucket and thus move the element and disconnect it from the arm to allow the bucket to dump.

7. A bucket, a draw member, a suspending arm and a holding device for the arm 125 comprising a rigid element pivotally connected directly to the bucket, said member movable to coact with the element to disconnect the device from the arm.

8. A bucket, a suspension arm pivoted to 130

the bucket, a draw member pivoted to the bucket, holding means between the arm and bucket releasable to permit swinging of the bucket relatively to the arm, and connecting 5 means between the arm and member coacting to limit the relative swing of the bucket, said member movable to disconnect the holding means from the arm.

9. A bucket, a draw member pivotally 10 connected to the bucket, said member having a reciprocable block, an actuating line for the bucket extending about the block to the member, and flexible connecting means from the block to the bucket.

15 10. A bucket, a draw member pivotally connected to the bucket, said member having a way, a block reciprocable along said way, and adjusting means to limit the travel of the block in the way, an actuating line 20 for the bucket extending about the block to the member, and connecting means from the block to the bucket.

11. A bucket, drag and return lines therefor, a draw member, connection between the 25 bucket and draw member, a trip for dumping the bucket, and additional connection between the member and bucket movable by slackening the drag line to maintain the member in position to permit free discharge 30 of material from the bucket in the dumping operation.

12. A drag bucket, a draw member, pivotal connection between the member and bucket, a trip for dumping the bucket, and additional 35 connections between the member and bucket to swing the member into position to permit free discharge of material from the bucket in the dumping operation.

13. A drag bucket, drag and hoist lines 40 therefor, a draw member for the bucket to which the drag line is connected, a suspension arm pivoted to the bucket and to which the hoist line is connected, a holding device 45 for the arm detachable from the arm by rocking of the member thereagainst to permit dumping of the bucket, and connections from the arm to the member to maintain the member in position to permit free discharge of material from the bucket in 50 the dumping operation.

14. A bucket, drag and hoist lines therefor, a holding device detachably connected between the hoist line and the bucket and provided with means acted upon by slackening 55 of the drag line to release the holding device to permit swinging of the bucket as to the hoist line, and setting means connected between the drag and hoist lines for reconnecting the device between the hoist line and bucket.

60 15. A bucket, a holding device for maintaining the bucket in material retaining po-

sition, a drag line connected to the bucket, a member connected to the device, operable by slackening the drag line to release the device from holding the bucket, and setting means for the device connected to the drag line and operable by taking up the drag line slack to reset the holding device to lock the bucket in material retaining position. 65 70

16. The combination with a bucket having a hoisting line, of a drag line to the bucket, and a drag line controlled disconnecting trip connected to the bucket and hoisting line, and provided with a trigger 75 acted upon by slackening the drag line to disconnect the trip and free the bucket for swinging relatively to the hoisting line.

17. The combination with a bucket having a hoisting line, of a drag line to the 80 bucket, a drag line controlled disconnecting trip connected to the bucket and hoisting line and provided with a trigger acted upon by slackening the drag line to disconnect the trip and free the bucket for swinging relatively to the hoisting line, and a reset means 85 for the trip connected between the drag and hoisting lines and operable by taking up the slack in the drag line to bring the trip into position for holding the bucket as to 90 the hoisting line.

18. A bucket having an inwardly swingable pivoted back, a hoisting member to which said back is connected, and a trip carried by the bucket to release the bucket 95 relatively to said hoisting member to thereby aid in expelling material from the bucket as the bucket swings relatively to the hoisting member.

19. A bucket embodying a tubular body 100 portion having front and rear ends, a pivoted back adjacent the rear end and swingable to open by travel toward the front end, and an extension section hinged to said back. 105

20. A bucket having a pivoted back, a trip for releasing said back, and a drag line having connection to the bucket and additional connection to control the trip.

21. A bucket having a forward end, a 110 suspending arm and back connected to the bucket, a holding device for maintaining the forward end of the bucket in material retaining position, and releasing means for the device to permit lowering of the forward end of the bucket and movement of the back theretoward. 115

In testimony whereof I affix my signature in the presence of two witnesses.

CHARLES A. FRAZER.
